Peter Van Nops & Abraham Wood, New York City,
Letters Patent No. 170 dated 21st March 1845

The Schedule referred to in these Letters Patent and making
part of the same.

To all whom it may concern:

Be it known that we, Peter Van Nops and Abraham Wood, both
of the City, County and State of New York, have invented or produced
a new and improved pattern of embellishment for Table forks, knives,
spoons, &c. and we hereby declare the following is a full and exact
description of the same, reference being had to the annexed drawings
which make a part of this Specification. Fig. 1 is the front

2

view of a fork with the pattern of foliage and curved lines as shown partaking the characters or styles of, &c, known as the Grecian and Louis 14th.

Fig 2. a view of the back of the fork having the same pattern as that which is on the front with the exception of the lower termination of the lines where they spread into foliage. This foliage on the back part shown at a, has the same character as on the front, the difference being, an enlargement of the leafwork.

Claim.

What we claim as our invention, and desire to secure by Letters Patent, is the combination and arrangement of the several ornamental parts as herein represented and set forth, forming a pattern of embellishment for Table forks, Knives, Spoons, &c.
